(57) **CLAIM**

The ornamental design for a toy block, as shown and described.

DESCRIPTION

FIG. 1 is a perspective view.

FIG. 2 is a back perspective view.

FIG. 3 is a front view.

FIG. 4 is a left side view.

FIG. 5 is a right side view.

FIG. 6 is a top view.

FIG. 7 is a bottom view.

FIG. 8 is a back perspective view; and,

FIG. 9 is a perspective environmental view of the present invention.

The broken lines in FIG. 9 represent the environment in which the toy block resides and forms no part of the claimed design.
